(57) **CLAIM**

The ornamental design for a remote transceiver, substantially as shown and described.

DESCRIPTION

FIG. 1 is a perspective view of the remote transceiver in accordance with the present invention;

FIG. 2 is a front view thereof;

FIG. 3 is a right side view thereof;

FIG. 4 is a left side view thereof; and,

FIG. 5 is a back view thereof.

The broken lines shown in the Figures are for illustrative purposes as an environment and form no part of the claimed design.

1 Claim, 4 Drawing Sheets

FIG. 1

FIG. 3**FIG. 2**

FIG. 4

FIG. 5
